UNITED STATES PATENT OFFICE

ROBERT JARDINE WATT, OF NORTH FERRIBY, ENGLAND

HEAT EXCHANGING APPARATUS

Application filed November 3, 1930, Serial No. 493,180, and in Great Britain April 4, 1930.

This invention has relation to heat ex-
changing apparatus and more particularly to
cooling apparatus for the abstraction of heat
from liquids. Its principal object is to pro-
5 vide an efficient heat exchanger especially a
cooler, which can be made of a formation of-
fering the minimum resistance to the flow of
fluid and with a surface the whole of which
constitutes useful heat exchanging area.

10 A further object of the invention is to pro-
vide an efficient cooler presenting a stream-
lined exterior formation to the cooling fluid.
Yet another object is to provide an efficient
cooler adapted to form a part of a surface
15 encountering a flow of cooling fluid.

In particular the invention is intended to
provide air-coolers for cooling water, lubri-
cating oil and the like for incorporation in
20 air craft and high speed water craft and land
vehicles, the purpose being to obtain a highly
efficient cooling action from the wind stream
without introducing extra head resistance or
drag.

These and other objects will appear more
25 fully from the following specific description
of two embodiments of the invention. In
the accompanying drawings:—

Fig. 1 is an end elevation of a cooler of
stream-line formation, one end plate being
30 removed to reveal the interior;

Fig. 2 is a longitudinal section on the line
II—II of Fig. 1;

Fig. 3 is a plan view of the inner side of a
cooler adapted to form part of a surface;

35 Fig. 3a is a plan view of the inner side at
the opposite end portion of the cooler of
Fig. 3.

Fig. 4 is a cross section thereof;

Fig. 5 is an end elevation of a header em-
ployed in the cooler of Figs. 3, 3a, and 4; and

Fig. 6 is a plan view of said header.

In the embodiment of the invention illus-
trated in Figs. 1 and 2, plates 1, 2 of a stream-
line contour forming adjacent walls of inlet
45 and outlet headers 3, 3a, 4 are connected at
their peripheries to opposite edges of a cor-
rugated sheet 5 bent to said stream-line con-
tour. The peripheries of said plates 1, 2 are
crenellated to fit the corrugations. The pe-
50 ripheries of plates 6, 7 forming the outer

walls of the headers 3, 3a, 4 are connected
to the edges of a smooth metal sheet 8 which
is also bent to the same stream-line contour
and forms the remaining walls of said head-
ers. The smooth sheet 8 is connected to the 55
corrugated sheet 5 along the crest of each
corrugation, producing a series of fluid ducts
9 communicating between the headers 3, 3a.
4. The remaining edges of the sheet 5 and
the sheet 8 are connected together in the trail-
ing edge of the stream-line shape. The inlet
header 3 is fitted with an inlet pipe 10 for
the fluid to be cooled and the outlet header
4 with an outlet or return pipe 11 for the
cooled fluid. The whole structure is carried 60
by a tubular support 12 to which the plates
1, 2, 6, 7 are secured where they are pene-
trated thereby. The various parts may be
secured or connected together by welding,
brazing, sweating and the like as circum-
70 stances require. If preferred the corrugated
and smooth sheets 5, 8 may each be in two
parts joined both at the leading and trailing
edges of the stream-line shape.

The cooler as a whole thus has a stream-
line formation bounded by the smooth metal
sheet or skin 8. Accordingly it may form
part of or be incorporated in an aerofoil,
strut, fairing and the like. In any case the
stream-line formation, in addition to its own
advantage of reducing resistance and drag,
ensures that the whole surface of the sheet
8 is air-swept and fully effective as heat ex-
changing area, the boundary layer effect be-
ing reduced to a minimum. The efficiency of
the heat exchanger is enhanced by the fact
that heat is transmitted by conduction from
the trough-parts of the corrugated sheet 5
to the exposed face of the smooth sheet 8. 85

The shape and size of the ducts 9 are de-
signed to furnish an aggregate heat exchange
area sufficient to ensure the required temper-
ature reduction of the fluid to be cooled in
its passage, at a given rate of flow, through
said ducts from the inlet header 3 to the out-
let header 4. Naturally the precise design
of the cooler will depend also upon the na-
ture of the fluid cooled, for example, oil,
water, steam and the like. Provision may
be made for regulating the cooling action 100

either by shrouding or by the inclusion in the inlet pipe line of a multi-way cock whereby a part or the whole of the fluid which would pass through the cooler may be short circuited to the return pipe line.

5. The form of cooler illustrated in Figs. 3 to 6 is more particularly designed to occupy a part of a surface which is in a fluid stream, that is, a covering for an aerofoil, nacelle, fuselage, boat hull or the like, the cooler being shaped in conformity with said surface. In the example illustrated the smooth sheet 8 constituting the outer or heat transfer wall and the corrugated sheet 5 forming the ducts 9 are of a plane formation. Obviously, however, they can be shaped to form a part or continuation of a surface of any desired kind. To enhance the strength and fluid-tightness of the cooler, the edges 13 of the sheet 8 are folded over the edges of the sheet 5 as shown in Fig. 3 and Fig. 3a. Fig. 4 shows the edges 13 before being so folded. The inlet and outlet headers 3, 3a, 4 each consist of a single-piece, bottomless body fitted respectively with an inlet and outlet pipe 10, 11. The bottom walls of these headers are provided by the sheet 8 when said header bodies are secured thereto. As before, the adjacent sides 1, 2 of the headers 3, 3a, 4 are connected to the corresponding edges of the corrugated sheet 5, the edges of said sides 1, 2 being crenellated in conformity with the corrugations to permit communication between the ducts 9 and the headers. Tongues 14 are formed at intervals along the sides 1, 2 and, projecting at right angles to said sides into the troughs between the ducts, facilitate the making of a good fluid-tight and mechanical connection.
20. Around the other sides, the headers 3, 3a, 4 are provided with a flange 15 over which the edges 13 of the smooth plate 8 are also folded, said edges being finally sealed all around by, for example, sweating. The inlet and outlet pipes 10, 11 being arranged at the ends of the headers 3, 3a, 4, said headers are made tapered as illustrated, a substantially uniform distribution of the fluid to be cooled between the ducts 9 being thereby obtained.
25. In other respects the construction and action of this cooler are similar to those of the cooler of Figs. 1 and 2.
- What I claim is:—
30. 1. Cooler comprising a smooth sheet metal body of stream-line formation, plates closing the sides of said stream-line body, partition walls arranged within said body parallel to said sides to divide off header spaces therein, a corrugated sheet metal body arranged within said stream-line body and between said partition walls, and inlet and outlet connections to said header spaces for fluid to be cooled, the crests of the corrugated sheet metal body being connected to the smooth sheet metal body

to form a series of fluid-ducts communicating between the header spaces.

2. Cooler comprising a smooth metal sheet, flat bottomless bodies laid flat upon and secured to one face of said sheet along opposite edges thereof to form inlet and outlet headers, inlet and outlet fluid connections to said headers, and a corrugated metal sheet secured to the same face of said smooth metal sheet between said headers, the crests of the corrugated metal sheet being connected to the face of the smooth sheet to form a series of fluid-ducts communicating between the headers. 70

3. Cooler as claimed in claim 2, wherein the headers each consist of a bottomless body of a tapered formation having a crenellated edge for connection to the corrugated metal sheet. 80

4. Cooler comprising a smooth heat exchanging wall exposed on one face to a cooling fluid, inlet and outlet headers bounded on the outside by transverse walls extending along opposite edges of said heat exchanging wall and on the inside by transverse walls extending across said heat exchanging wall at 85 a distance from the outside walls, and a corrugated wall secured to the other face of the heat exchanging wall and extending between the inside walls of the headers, the corrugations thereby forming a series of fluid ducts 90 communicating in parallel between said headers. 95

5. Cooler comprising a smooth heat exchanging wall having one face exposed to a cooling fluid, inlet and outlet headers bounded on the outside by transverse walls secured to opposite edges of the other face of said heat exchanging wall and on the inside by crenellated transverse walls extending across 100 said other face of the heat exchanging wall at a distance from the outside walls, and a corrugated wall having the crests of its corrugations secured to the aforementioned other face of the heat exchanging wall and its corrugated edges secured to the crenellated edges of the inside walls of the headers, a series of fluid ducts communicating in parallel 105 between said headers being thereby formed. 110

6. Cooler comprising a cooling wall having 115 a smooth exposed outer face and shaped to form a stream-line body, inlet and outlet headers for fluid to be cooled extending from front to rear of said stream-line body, and a corrugated wall secured to the inner face of said cooling wall and between said headers, the corrugations forming a plurality of transverse fluid ducts communicating in parallel between said headers. 120

Dated this 11th day of October 1930.

ROBERT JARDINE WATT.
